[57] **CLAIM**

The ornamental design for a digital telephone exchange equipment cabinet or similar article, as shown and described.

DESCRIPTION

FIG. 1 is a front elevational view of a digital telephone exchange equipment cabinet or similar article showing my new design;

FIG. 2 is a left side elevational view thereof;

FIG. 3 is a top plan view thereof;

FIG. 4 is a rear elevational view thereof;

FIG. 5 is a front elevational view thereof with the doors open; and

FIG. 6 is a rear elevational view thereof with door open.

The right side is a mirror image of the left side thereof; the bottom is plain and unornamented.
